WORLD TIME CLOCK

Vidig O. Jacobs, Chicago, Ill.

Application May 9, 1936, Serial No. 78,873

9 Claims. (Cl. 58—43)

This invention is a time clock capable of indicating the time of day or night at any point throughout the world.

An important object of my invention is the provision of a clock capable of indicating the hour, minute and second of time in all the principal world time zones.

A further object of my invention is the provision of a simple means of knowing the time of day or night at any point in the world without the necessity of computing the same.

The further important object of my invention is the provision of a timepiece which shows the time at any point in the world at a single glance.

15 A still further object of my invention is the provision of a flat, thin time indicating apparatus suitable for mantles, radios, airplanes and automobiles.

A still further object of my invention is the provision of a timepiece capable of indicating world time and the further provision of a means to emphasize the time in any zone by directing light upon the particular time zone or zones of interest.

25 Other and still further objects of my invention will be apparent from the disclosures in the accompanying drawing and specification.

The invention in preferred form is illustrated in the drawing and herein furthermore fully described.

30 On the drawing:

Figure 1 is a front elevational view of the clock. In the upper left portion of said figure, the glass is broken to show the map bearing face of the clock. The minute- and second-hands are shown in elevation. In this figure the face is also broken to show the geared-edged hour indicating discs. At the right of Figure 1, one hour indicating disc is broken to show one of the light directing discs which are mounted immediately behind the hour indicating discs, and the gears which rotate them.

Figure 2 is a sectional view taken on the line 2—2 of Figure 1 showing in detail the glass face, the minute-hand, second-hand and shafts bearing the same, and the map bearing face of the clock. An hour indicating disc and a light directing disc appear in the background. Also shown in section is the segmented two-toothed drive gear and the four-toothed gear meshing therewith. Also shown in the section is the eight-toothed gear which meshes with the teeth on the hour indicating discs. The clockwork mechanism is also indicated.

55 Figure 3 is an enlarged front elevational view

of a section of the gear mechanism taken on the line 3—3 of Figure 2, the hour numerals being omitted. This figure shows the inter-relation of the segmented drive gear, the four and eight toothed gears and the geared-edged hour indicating discs. Figure 4 is a fragmentary front elevational view of a portion of the clock face, showing the map and meridians thereon and particularly one of the pair of identical semi-annular apertures in the clock face.

As shown on the drawing:

The reference numeral 1 indicates a spring or electric motor driven clockwork mechanism which furnishes the power for the said clock and regulates the same. The clockwork is to have 15 standard setting, regulating and alarm mechanisms.

Connected to said clockwork mechanism and so regulated as to make one complete clockwise revolution every sixty minutes is a hollow shaft 2, which carries, immediately outside the clockwork casing, the two toothed segmented gear 2a, and at its outer portion, the minute-hand 2c.

Shaft 3 is connected to the clockwork mechanism and is so regulated as to make one complete clockwise revolution every sixty seconds. It passes longitudinally through the hollowed center of shaft 2, being smaller in diameter and longer than said shaft, and carries, at its extreme outward portion, the second-hand 3a.

Being fixedly mounted on shaft 2, the segmented gear 2a turns clockwise once every hour. Every time a complete revolution of said gear is accomplished, the two teeth 2b on said segmented gear, come into contact with the teeth 35 on the four-toothed gear 4, rotating the gear and the shaft 4a, to which it is fixedly mounted, and eight-toothed gear 5, one half of a complete revolution, counter-clockwise. Shaft 4a is not otherwise connected to the clockwork mechanism than 40 through the gear system described above. Suitable bushings or bearings may be used on the ends of said shaft.

The eight-toothed gear 5 is interposed between and meshed with two geared-edged rotating circular hour indicating discs 6. Each disc has ninety-six teeth on its periphery, four teeth to each hour portion. These discs are rotatably mounted on axles 6a. Near their outer rims said geared hour indicating discs each have two sets 50 of numerals, twenty-four in all, running numerically counter-clockwise from 1 to 12, equally spaced around the periphery of said discs. The numerals may be mounted on translucent material or the material surrounding them may be cut

away so that they will show distinctly when light is directed upon them as later herein set forth.

The gear ratio of eight toothed gear 5 and the geared-edged hour indicating discs is 1 to 12. Every half revolution of shaft 4a rotates gear 5 four teeth in a counter-clockwise direction rotating discs 6 four teeth in a clockwise direction.

As shown in Figures 1 and 2, axially mounted behind hour indicating discs 6 are toothed circular discs 9 in which is a translucent aperture 9a, said aperture being the width of one hour portion in disc 6. The discs 9 and apertures 9a serve the purpose of directing light, furnished by bulbs 14 only one of which is shown, the other bulb being in the same relative position on the left as is bulb 14 indicated in Figure 1, upon the hour on any desired time meridian.

The disc 9 is rotated by turning knob 12a, which is fixedly connected to shaft 12. Gear 11 is fixedly connected to shaft 12, rotating as the knob 12a is turned. Gear 11 meshes with gear 10, which in turn meshes with the teeth on the outer periphery of disc 9, allowing rotating motion both clockwise and counter-clockwise.

Shaft 12, by means of knob 12a, may be pulled out or pushed in, making contact through electric switch 13, with a source of electric current, which lights bulbs 14. Gear 11 is relatively wider than gear 10, such that it remains meshed with said gear 10 when knob 12a and shaft 12 are pulled out to operate the switch 13.

The face of said clock, indicated by numeral 7, consists of a flat oval surface, on which is imposed a circular map of North and South America, 35 and a small section of Asia, on one-half thereof, and a circular map of Europe, Africa, Australia and the remainder of Asia, on the other section thereof. Also shown on said maps, and indicated by numeral 7b, are the principal time meridian lines. The spaces between these meridian lines 40 are widened at the lower sections thereof as they approach the semi-annual apertures 7c, (described hereinafter) so that the lines thus formed coincide with the hour markings on hour indicating discs 6.

The clock face 7 is cut by two semi-annual apertures 7c, extending from a point half way down the map section on either side of said face, exposing the numerals on the lower halves of 50 hour indicating discs 6. Twelve hour numerals are thus exposed on each half of said clock, twenty-four in all being in view, representing the twenty-four hours of time extant throughout the world.

Mounted at a slight angle as regards the clock face 7 is an oval rim 7d on which are imposed the minute numerals 7e. The entire clock face is covered by a transparent glass 8.

Looking at the clock from the front through the glass 8, the two circular maps 7a, the meridian lines 7b, the semi-annual apertures 7c, the rim 7d, the minute numerals 7e, the minute-hand 2c, the second-hand 3a, and twelve numerals (6b) on each disc, representing twenty-four hours of the 65 day and night throughout the world, are visible. Knobs 12a, below the clock face are also visible. In preferred form the numerals 6b on disc 6 are colored black and white, white representing daytime, black representing night. Twelve white 70 numerals and twelve black numerals are, therefore, always visible through semi-annual apertures 7c.

In assembling the clock, the time indicating discs 6 must be so aligned in relation to gear 5 that the white daytime numerals 6b on one disc

are visible through aperture 7c on one side and the twelve black numerals, representing night, are visible on the other side through the other semi-annual aperture 7c.

The entire mechanism is to be so constructed 5 that the setting mechanism of the clockwork mechanism will rotate the hour indicating discs 6 and the minute hand 2c.

In operation the clock is set to indicate the proper time and the clockwork and mechanism 10 is started. The second-hand rotates once each minute. The minute-hand makes one complete revolution every sixty minutes. When one complete revolution of the minute-hand has been accomplished the segmented gear 2a comes into 15 contact with four-toothed gear 4, the teeth 2b rotating gear 4 one-half of a revolution. Gears 4 and 5 being fixedly mounted on the same shaft 4a, a half revolution of the shaft imparts a half revolution or a movement of four teeth to gear 20 5. Gear 5 being meshed with the teeth on the periphery of hour indicating discs 6, said discs are rotated four teeth in a clockwise direction. The rotation thus imparted to the discs thus bring another hour numeral directly beneath the out- 25 spread ends of the time meridians 7b, indicating one hour later time in each time meridian.

Hour numerals 6b may be stamped out of discs 6 or may be mounted on translucent material so that the light passing through apertures 9a in 30 light directing discs 9 will emphasize any desired hour in any meridian appearing through semi-annual clock-face apertures 7c.

It will be seen from the above disclosure that I have invented a timepiece capable of indicating 35 time throughout the world. While I have described and illustrated my time clock in considerable detail, I do not wish to be limited to the exact construction disclosed herein other than is necessitated by the prior art.

Having thus described my invention, I claim:

1. In a clock, the combination of a glass covered face, world maps and time meridians imposed upon said face, minute- and second-hands rotating in front of said face, semi-annual apertures 45 in said face and a plurality of clockwise rotating hour indicating discs visible through the apertures in said face.

2. In a time indicating mechanism, the combination of a clockwork mechanism, a two-toothed 50 segmented gear operated by said clockwork and rotating one every hour, a four-toothed gear meshing with said segmented gear and rotated thereby, an eight-toothed gear fixedly mounted to said four-toothed gear and rotating therewith, 55 a plurality of hour indicating discs meshed with said eight-toothed gear, a clock face having formed therein a pair of semi-annual apertures, a map on said clock face, meridian lines on said map, said hour indicating discs rotating beneath 60 the map and meridian lines, said hour indicating discs bearing hour numerals visible through the semi-annual apertures in said clock face exposing said hour numerals in registry with the spaces between said meridians.

3. In a time indicating apparatus, the combination of a clockwork mechanism, minute- and second-hands attached thereto and operated thereby, a flat clock face having a pair of spaced apart semi-annual apertures therein, maps on 70 said clock face, a plurality of time meridians indicated on said maps and a pair of hour indicating discs mounted and rotating hourly clockwise beneath said time meridians and visible through the semi-annual apertures in said clock 75

face indicating the time on each of said time meridians.

4. In a time clock the combination of a clockwork mechanism, minute- and second-hands operated thereby, a plurality of cooperative gears, a plurality of hour indicating discs connected thereto and rotated thereby, a face on said clock having a plurality of semi-annular apertures therein, time meridians indicated on said face and terminating in identical segments at the periphery of the apertures in said clock face, said clockwork mechanism and cooperative gears adapted to relatively and progressively control the relative position of the minute- and second- 10 hands and hour indicating discs relative to the face of said clock and time meridians thereon.

5. In a timepiece the combination of a clockwork mechanism, an ovalescent clock face having a pair of identical semi-annular apertures therein, 20 minute numerals on the periphery of said face, a plurality of meridian-lined maps imposed on said face, minute- and second-hands rotated by said clockwork mechanism in spaced relation to said face and numerals thereon, and adapted to 25 indicate the minute and second of the hour, hour indicating discs rotating behind said map faces and clockwork operated means adapted to progressively regulate the relative positions of said hour indicating discs visible through the apertures in 30 said clock face once each hour in relation to said meridian lines on said maps.

6. In a timepiece the combination of an ovalescent clock face having a plurality of semi-annular apertures therein, numerals on the periphery of 35 said clock face, a clockwork mechanism, a minute-hand and a second-hand rotated clockwise thereby in relation to said numerals on the periphery of said ovalescent clock face, a plurality of substantially circular cartographic representations of hemispheres of the earth placed side 40 by side on said clock face, time meridians on each of said cartographic representations, the space between said time meridians widened to terminate in equal segments at said apertures in 45 said clock face, a plurality of hour indicating discs rotating clockwise by said clockwork mechanism in predetermined relation to said apertures in said clock face and said time meridians terminating 50 thereof, thereby indicating the hour in each of said time meridians.

7. In a time indicating mechanism the combination of a face having a plurality of semi-annular apertures therein, a plurality of circular maps and

spaced time meridian lines on said face, the space between said time meridians terminating in equal segments at said apertures, a plurality of interconnected discs bearing hour indicating numerals and rotating behind said face, part of said numerals being exposed through the apertures in said face and adapted to fall into registry with said segments thereby indicating the time thereon and a means to direct light upon any selected hour indicating numeral appearing within said 10 apertures.

8. In a time indicating device the combination of a clockwork mechanism, a segmented gear rotated by said clockwork mechanism, a shaft, a first gear carried by said shaft and adapted to be 15 rotated hourly by said segmented gear, a second gear mounted on said shaft and rotatable therewith, a plurality of gear edged discs adapted to be rotated by said second gear in a clockwise direction, hour numerals on said gear-edged discs, 20 a clock face having a plurality of semi-annular apertures therein through which the hour numerals on said discs are visible, a map and time meridians on said clock face, the spaces between said time meridians terminating in equal segments at the apertures in said clock face, the numerals on said discs being adapted to fall into registry with the spaces between said meridians and indicating the time thereon.

9. In a time indicating device, the combination 30 of an ovalescent face having a pair of identical semi-annular apertures therein, minute numerals around the periphery of said ovalescent face, a clockwork mechanism, minute and second-hands rotated by said clockwork mechanism above said 35 clock face, a pair of substantially circular upright hemispherical maps on said clock face, each of said maps being in bottom registry with one of the semi-annular apertures in said clock face, meridian lines on said maps terminating 40 equi-distant from one another and having equal spaces therebetween at the apertures in said clock face, a pair of hour indicating discs rotating clockwise under said clock face, hour numerals around 45 the periphery of said discs and adapted to fall into registry with the spaces between said meridian lines, and means whereby said clockwork mechanism rotates said hour indicating discs hourly the distance of the space between two adjacent meridian lines in a clock-wise direction thereby 50 to indicate the hour thereon.

VIDING O. JACOBS.
